UNITED STATES PATENT OFFICE.

GUSTAV SITTMANN AND WALTER H. PITTS, OF BROOKLYN, NEW YORK.

DESIGN FOR A CASE FOR COIN-CONTROLLED MACHINES.

SPECIFICATION forming part of Design No. 23,190, dated April 10, 1894.

Application filed March 8, 1894. Serial No. 502,910. Term of patent 7 years.

To all whom it may concern:

Be it known that we, GUSTAV SITTMANN and WALTER H. PITTS, citizens of the United States, residing in Brooklyn, in the county of Kings and State of New York, have invented and produced a new and original Design for Cases for Coin-Operated Machines, of which the following is a specification, reference being had to the accompanying drawing, showing a part thereof.

The accompanying drawing is a perspective view of our design.

A is the vertical front panel of the case, provided with scroll work, B, in relief.

C, D and E are openings in the upper part of the front of the case, and F is the slot for the introduction of a coin.

G, G represent raised scroll work at the sides of the front of the case, and H scroll work at the top.

I is the end panel of the case, provided with scroll work, J.

What we claim as new, and desire to secure by Letters Patent, is—

The design for a case for coin operated machines set forth and described.

GUSTAV SITTMANN.
WALTER H. PITTS.
